INVENTOR
HENRI CHIREIX
BY *H. G. Moore*
ATTORNEY

UNITED STATES PATENT OFFICE

HENRI CHIREIX, OF PARIS, FRANCE

ACOUSTIC DEVICE

Application filed May 2, 1929, Serial No. 359,823, and in France May 3, 1928.

This invention relates to acoustic devices. More particularly it relates to the means for supporting the diaphragm of such a device.

The object of the present invention is to disclose a number of improved methods of supporting the diaphragm of an acoustic device such as a sound reproducer.

According to the present invention a supporting band or strip made from flexible material is placed underneath the edge of the sound reproducer diaphragm so as to form a flange of circular shape tending and adapted to counteract slipping of the base of the cone diaphragm in its plane. This supporting band is folded or curved back or thickened or reinforced, as shown.

In the case of coupling two conical tympana opposing each other at their apices, another improvement consists in choosing one of them of a diameter considerably smaller than the other. Among other things, this causes an improvement in the faithfulness of reproduction.

The invention will be better understood by reference to the accompanying drawing and the following description thereof covering certain embodiments by way of example. In the drawing,

Figure 1 illustrates one form of my invention,

Figures 2 to 5 illustrate modifications thereof, and Figure 6 illustrates a modification having a pair of tympana.

In the drawing, A designates the band of soft material which the periphery of the tympanum E engages. B is the groove in which the band A is lodged. Figure 1 shows a solution in which the band A is bent back so as to form a flange or collar. The two thicknesses of the material may be preferably held in their respective positions by sewing with thread, gluing or cementing, clips, or the like.

Referring to Figure 2, the band A comprises a portion raised at a right angle along the peripheral border or edge of the groove B.

Figure 3 comprises a band A of two superposed thicknesses, the inside diameter of the

second thickness or layer being larger than that of the tympanum.

Figures 4 and 5 show two other modifications in which the band A is held by the aid of a circular spring F which is preferably in the form of a metallic "reed". The band A is folded or bent back all around in the groove B.

Figure 6 shows a modification in which two tympana of different diameters are arranged so that they oppose each other at their apices. The edges of the tympana are supported as in the other modifications.

I claim:

1. Acoustic apparatus comprising at least one support, a supporting element lodged in said support and comprising a band made from elastic material curved back around a circular spring so as to form a concave surface, and at least one conical diaphragm whose rim bears upon said concave surface. 65 70

2. Acoustic apparatus comprising two supports of diaphragms, a supporting element lodged in each support, each element supporting the border of a conical diaphragm and presenting a concave surface in the neighborhood of the line of support of this border, a portion of said concave surface situated outside the periphery of the diaphragm forming an angle with the plane of the base of the cone which is much larger than the angle between the generatrix of the cone and the plane of its base, the two diaphragms being united at their apices and one having a diameter considerably smaller than that of the other. 75 80 85
